REFRIGERATING APPARATUS

Carl A. Stickel, Dayton, Ohio, assignor to General
Motors Corporation, Dayton, Ohio, a corpora-
tion of Delaware

Application January 28, 1939, Serial No. 253,419

5 Claims. (Cl. 62—89)

This invention relates to refrigerating apparatus and more particularly to means for adding moisture to the atmosphere within the food compartment of a refrigerator cabinet.

There is a condition of a relatively dry atmosphere present within the food storage compartment of refrigerator cabinets. This condition is brought about by lowering the temperature of the atmosphere within the refrigerator cabinet by means of a temperature reducing medium which is at a temperature below that of the surrounding atmosphere. This cooling, by the low temperature medium, causes the dew point of the warmer atmosphere to lower, which in turn causes a part of the moisture carried by the atmosphere to condense upon the surface of the cooling medium. The removal of this moisture dehumidifies the atmosphere and places the same in a condition whereby it can pick up more moisture when the temperature thereof is increased by normal circulation in contact with the food articles placed in the refrigerator cabinet. This tends toward considerable drying of the food articles.

It is an object of my invention to overcome this drying effect of the circulating atmosphere by introducing a small amount of moisture into the atmosphere at selected intervals.

It is a further object of my invention to provide an atomizing device within the food storage compartment of a refrigerator cabinet which will derive its power for operation from a device normally a part of the refrigerator cabinet which is capable of having motion imparted thereto.

It is a still further object of my invention to provide an atomizing device for introducing moisture into the food storage compartment of a refrigerator cabinet which can be operated concomitantly with movement of a device normally a part of the refrigerator cabinet which is capable of having motion imparted thereto.

Further objects and advantages of the present invention will be apparent from the following description, reference being had to the accompanying drawing wherein a preferred form of the present invention is clearly shown.

In the drawing:

Fig. 1 is a horizontal fragmentary cross-sectional view of a refrigerator cabinet embodying a modified form of my invention;

Fig. 2 is a fragmentary cross-sectional view taken substantially along the line 2—2 of Fig. 1; and

Fig. 3 is an enlarged cross-sectional view of the atomizing nozzle.

Briefly, my invention consists of an atomizing device for introducing moisture into a refrigerator cabinet, and is comprised of a pump, a water reservoir, and a spray or atomizing nozzle. The pump of my atomizing device is operatively connected to a normally existing and movable part of the refrigerator cabinet in such a manner that the pump is operated when the part is moved. This provides a means for imparting power to the atomizing device independent of any external connections and without the necessity of adding elements to an already existing refrigerator cabinet structure for creating the power. Since my atomizing device is operatively connected to a part of the refrigerator cabinet which may be imparted with motion at selected intervals, moisture will be injected into the atmosphere within the cabinet each time the part is moved.

In Figs. 1 and 2 I provide a refrigerator cabinet 80 having an inner metal wall 81 which provides an enclosure forming a food storage compartment 82. This food storage compartment 82 is provided with an evaporating means 30, for maintaining proper temperature conditions within the compartment. The evaporating means placed within the food storage compartment 82 is adapted to be connected to a refrigerant liquefying means. The food storage compartment 82 is provided with a door opening 83, which opening is adapted to be closed by means of a door 84. A latching mechanism 85 is provided on the door 84 and a strike and keeper 86 is provided on the door opening 83. A latch bolt 87 extends from the latch mechanism 85 and is adapted to engage the strike and keeper 86 in order to retain the door 84 in a closed position with regard to the door opening 83. A handle 88 extends from the latch mechanism 85 for permitting manual operation of the latch mechanism for withdrawing the bolt 87 from the strike and keeper 86 to permit opening of the door.

A second means is also provided for removing the bolt 87 from the strike and keeper 86. This means consists of a foot operated pedal 90 pivotally mounted at 81. A pin 92 engages an extending arm 95, of the foot pedal 90, and an ear 93 extending from the bottom wall of the refrigerator cabinet 80, thereby providing the pivotal mounting point. This pedal mechanism is located close to the floor so that the pedal 90 may be operated by the foot pressure of an operator. The ear 93 to which the foot pedal 90 is pivotally mounted is secured to the lower wall of

the refrigerator cabinet 80 by any suitable means such as welding or brazing. A rod 93 is provided within the wall of the refrigerator cabinet and is adapted to extend vertically therein to a point adjacent the latch mechanism 85. The lower end of the rod 93 is provided with an angularly extending arm 94 which engages the extending arm 95 of the foot pedal 90 and is pivotally pinned thereto at 96. A downward movement of the foot pedal 90, about its pivot point 92, will cause a downward vertical movement of the rod 93. This rod 93 provides an operating link between the foot pedal lever 95 and the latch operating mechanism 85. It also initiates operation of an atomizing device hereinafter described. A spring 97 has one end thereof attached to the arm 95 of the food pedal, at 98, and the other end attached to a bracket 99 secured to the lower wall of the refrigerator cabinet 80. This spring 97 returns the foot pedal to its normal released position. A stop 100, provided on the rod 93, controls the vertical movement of the rod 93 and the return of the foot pedal 90.

The upper end of the rod 93 engages a lever 101 which is pivoted at 102, the lever 101 engaging the rod 93 and being pinned thereto by means of the pin 103. The end 104 of the lever 101 is provided with a cam shaped face and engages a roller 105 carried by a plunger 106 slidably mounted within a cage 108 carried by the door opening frame 83. The plunger 106 extends into the strike and keeper 86, the end thereof engaging the bolt 87 of the latch mechanism 85. The plunger 106 is normally retained in the position as shown on the drawings by means of a spring 107, which spring presses the roller against the cam face of the end 104 of the lever 101.

My atomizing device comprises a pumping mechanism 110, a water reservoir 125 and a liquid spray nozzle 53a. The elements of my atomizing device have been disclosed within a wall of the refrigerator cabinet adjacent the door opening 83 and in close proximity to the latch mechanism 85, however, these elements can be positioned in any location on the cabinet as long as the atomizing device is so positioned as to inject the spray into the food storage compartment.

The pumping mechanism 110 consists of a cylinder 111 and a piston 112. A coil spring 113 is provided between the bottom wall of the piston 112 and the end wall 114 of the cylinder 111 for producing a forward stroke of the piston 112 within the cylinder. A connecting rod 115 has one end thereof attached to the piston 112, the other end extending beyond the end wall 114 of the cylinder 111. The extending end of the connecting rod 115 is provided with an enlarged head 116 which engages a U-shaped bracket 117. This U-shaped bracket 117 has one leg thereof attached to the upper end of the rod 93 and is riveted thereto as indicated at 118. The other leg 119 of the bracket 117 is provided with a fork therein which is adapted to be positioned around the extending end of the connecting rod 115 and engage the head 116. This bracket 117 provides an operating connection between the foot pedal operating mechanism and the atomizing device in order to produce a concomitant operation of the two devices when the foot pedal is operated.

The water reservoir 125 is provided with an outlet connection 126 which connects the lowermost portion of the reservoir 125 with the pumping chamber of the cylinder 111. A filler opening 127 is provided in the upper end of the water

reservoir 125 through which water may be admitted into the reservoir from time to time as needs require. The filler opening 127 extends into the food compartment 82 to permit easy access thereto. The atomizing device 53a is also positioned within the food storage compartment 82.

When the foot pedal 90 is moved downwardly, the rod 93 is imparted with a downward motion which causes the lever 101 to be pivoted in a counter-clockwise direction around the pivot 102. This movement of the lever 101 causes the end 104 thereof to move upwardly to force the plunger 106 into engagement with the bolt 87 of the latch mechanism 85, thereby forcing the bolt 87 out of engagement with the strike and keeper 86. At the same time, the downward movement of the rod 93 causes the U-shaped member 117 to pull downwardly on the head 116 of the piston rod 115, thereby forcing the piston 112 to move in a downward stroke against the pressure of the spring 113. When the piston 112 is in its lowermost position within the cylinder 111, the top end thereof will be below the level of the outlet connection 126 between the water reservoir 125 and the cylinder 111, thereby permitting water to drain by gravity from the water reservoir 125 into the chamber between the end of the piston and the head of the cylinder.

Upon release of the foot pedal 90 by the operator, the pedal is permitted to return to its normal released position as shown on the drawings. The rod 93 will be moved in an upward direction by the release of the foot pedal 90. Upon this movement of the rod 93, the U-shaped bracket 117 will move upwardly, since it is carried by the rod 93, and the end 119 of the bracket 117 will leave the head 116 of the piston rod 115. At the same time, the end 104 of the lever 101 will be rotated in a clockwise direction into its normal position as shown on the drawing, permitting return of the plunger 106. Since the piston is now in the lower-most position of its stroke, the spring 113 will be under compression. The expansion of the spring 113 will tend to force the piston upwardly until the end of the piston 112 engages the head of the cylinder 111. The pressure thus created upon the water within the pumping chamber of the cylinder 111 will force the water through a discharge valve 120 provided in the head of the cylinder. The discharge of the water through the valve 120 creates a pressure within the chamber 121 and the pipe 122. The pipe 122 connects the pressure chamber 121 with the atomizing nozzle 53a and is provided for conducting the water from the pressure chamber to the nozzle. Since this chamber and pipe, 121 and 122 respectively, are now under pressure, the water will be forced to exit through the atomizing nozzle in a thin film-like spray passing between the surfaces of the valve 10a and the valve seat 11a.

It is thus seen that by the arrangements of my devices, I have provided a means whereby an atomized vapor may be added to or injected into the atmosphere of a refrigerator cabinet at selected intervals, since the atomizing device is caused to function each time a movable part of the refrigerator cabinet is imparted with motion. These devices are not only operated concomitantly with movement of the door operating mechanism, but also receive their energy for operation from this movement. These devices, thereby have particular advantage in the fact that they require no external source of power for opera-

tion, and may be readily installed on any refrigerator cabinet which has a movable part available. While I have shown my devices as being constructed and arranged for cooperation with movement of a door or a door operating mechanism of a refrigerator cabinet, the forms of power and operating mechanisms are not limited to these particular sources, but can include any movable part of a refrigerator cabinet which is a normal operating mechanism usually positioned on refrigerator cabinets, and which is capable of having motion imparted thereto either mechanically or by a power driven device.

This application is a continuation in part of my application for Refrigerating apparatus Serial No. 56,987 filed December 31, 1935, now Patent No. 2,149,799, granted March 7, 1939.

While the form of embodiment of the invention as herein disclosed, constitutes a preferred form, it is to be understood that other forms might be adopted, all coming within the scope of the claims which follow.

What is claimed is as follows:

1. Refrigerating apparatus including an insulated refrigerator cabinet having a door and a door opening, means for providing latching engagement of said door with said cabinet, means for disengaging the latching engagement of said door with said cabinet, an atomizer within said cabinet, said atomizer being interconnected with said latch disengaging means whereby said atomizer is energized concomitantly with movement of said latch disengaging means.

2. Refrigerating apparatus including an insulated refrigerator cabinet having a door and a door opening, latch means for retaining said door in said door opening, means for cooling the interior of said cabinet including an evaporator operating at a temperature which continuously withdraws moisture from the air circulating with- 40

in said cabinet to reduce the relative humidity of said air, a liquid atomizing means for providing moisture to the air circulating in said cabinet to replace the moisture removed from said air by said evaporator and sustain the relative humidity of said air, said means being energized by movement of said latch means for spraying said moisture within said cabinet.

3. Refrigerating apparatus including an insulated refrigerator cabinet having a door and a door opening, means for providing latching engagement of said door with said cabinet, means for disengaging the latching engagement of said door with said cabinet, means for cooling the interior of said cabinet including an evaporator operating at a temperature which continuously withdraws moisture from the air circulating within said cabinet to reduce the relative humidity of said air, a liquid atomizing means for providing moisture to the air circulating in said cabinet to replace the moisture removed from said air by said evaporator and sustain the relative humidity of said air, said means being energized by movement of said latch means for spraying said moisture within said cabinet.

4. A cabinet having a door opening and a door for closing the opening, latch means for latching the door in closed position, operating means for operating the latch means and means energized coincidentally with the operation of the operating means for hydraulically forcing a liquid into said cabinet.

5. A cabinet having a door opening and a door for closing the opening, latch means for latching the door in closed position, means operated coincidentally with the operation of the latch means for storing potential energy, and means operated by the stored potential energy for hydraulically spraying a liquid into the cabinet.

CARL A. STICKEL.
